UNITED STATES PATENT OFFICE.

JOHN W. JEPSON, OF BUFFALO, NEW YORK, ASSIGNOR, BY MESNE ASSIGNMENTS, TO
U. S. LIGHT & HEAT CORPORATION, OF NIAGARA FALLS, NEW YORK, A CORPORA-
TION OF NEW YORK.

AUTOMATIC ELECTRIC REGULATOR.

1,197,209.

Specification of Letters Patent.

Patented Sept. 5, 1916.

Original application filed November 29, 1907, Serial No. 404,271. Divided and this application filed January 17, 1916. Serial No. 72,512.

To all whom it may concern:

Be it known that I, JOHN W. JEPSON, a citizen of the United States, residing at Buffalo, in the county of Erie and State 5 of New York, have invented new and useful Improvements in Automatic Electric Regulators, of which the following is a specification.

My invention relates to improvements in 10 automatic electric regulators.

The broad features of my invention are covered by my co-pending application Serial No. 404,271, filed November 29th, 1907, "Automatic electric regulators", of which 15 this application is a division.

One of the objects of my invention is to provide a regulator which shall be simple in construction, stable in operation and which shall regulate within close limits.

Another object is to reduce sparking to a 20 minimum in a regulator having vibrating short-circuiting contacts.

In the accompanying drawings I have illustrated diagrammatically one embodiment of the invention.

The regulator is connected so as to regulate the voltage impressed upon the circuit 1, 2, across which translating devices 3 are connected. The translating devices may 25 assume various forms. The regulator may, of course, be connected to regulate the field strength of a generator, or it may be connected in various other ways. The regulating medium selected for illustration is in 30 the form of a variable pressure rheostat 4 comprising preferably a series of resistance plates of carbon or other material. This variable pressure rheostat is connected between the translating devices and the source 35 of electrical energy in order to suppress any tendency toward an excessive voltage which might otherwise be impressed on said translating devices. The resistance of the rheostat is varied by varying the pressure applied to one end thereof. The other end is held against a stationary abutment. The movable end is engaged by the end of a bell crank lever 5, actuated by an electro- 40 magnet or operating winding 6 which, when energized, draws up the plunger 7 against the action of the spring 8.

The operating winding 6 is connected

across the circuit 1, 2, in series with a resistance 9. Its circuit may be traced from conductor 1 to conductors 10, 11, winding 6, 55 conductor 12 and resistance 9 to the negative conductor 2. The operating winding 6 is normally deenergized, being short-circuited by a pair of separable electrodes or contacts 13 and 14, one of which is adapted 60 to vibrate rapidly to open and close a shunt circuit around said operating winding 6. The stationary contact 13 is preferably adjustable and the movable contact 14 is mounted upon the free end of a 65 vibratile reed 15. This reed is adapted to be set in vibration by a controlling magnet which is composed of two coils 16 and 17. The main coil 16 is preferably connected across the circuit to be regulated between 70 the variable pressure rheostat 4 and the translating devices so as to be subjected to the same voltage as said translating devices. The circuit of the main coil 16 extends from the positive main 1, through conductor 10, 75 conductor 18, coil 16, conductor 19 to the negative main 2. The modifying coil 17 is connected in parallel with the separable contacts 13 and 14 and hence is adapted to be short-circuited by said contacts when the 80 resilient reed 15 is in normal position and is adapted to be energized as soon as said reed is drawn down. The coil 17 is illustrated as being connected in series with the operating winding 6 and hence is deenergized when said winding is deenergized, being short-circuited by the contacts 13 and 14, but is energized whenever said winding 85 is energized by the separation of said contacts. It is apparent, however, that said coil 17 need not be connected in series with said operating winding 6 but may be connected in other relations as long as said modifying coil 17 opposes the main coil 16 when energized and hence acts differentially 90 to reduce the effectiveness of said main coil. Said coil also compensates for the varying reluctance of the air gap between the resilient reed 15 and the core of the controlling magnet, as said reed is moving up or down 100 under the influence of said magnet. When the reed is drawn down under the influence of said controlling magnet, thereby opening the short-circuit above referred to, the cir-

cuit through the modifying coil 17 may be traced as follows:—from the positive main 1 through the conductor 10, conductor 11, operating winding 6, conductor 12, modifying coil 17, conductor 20 and resistance 9, back to the negative main 2.

The operation of the system is substantially as follows: Assuming that it is desired to maintain a given voltage upon the 10 translating devices 3 and that the voltage of the source of electrical energy is higher than said given voltage, there will be therefore a continuous tendency for the voltage impressed upon the translating devices to 15 rise above the desired value. The main coil 16 of the controlling magnet responds to this tendency toward higher voltage, being subjected to the same voltage as said translating devices. Consequently the increased energization of said main coil will 20 cause the resilient reed 15 to be attracted, thereby opening the short-circuit around the operating winding 6 and the modifying coil 17 in series therewith, and permitting the 25 energization of both these windings. As a result of the energization of the winding 6, the resistance 4 is increased, due to the decrease in pressure applied through the bell crank lever, and as a result, the voltage will 30 fall slightly. The coil 16 thereby tends to weaken and permit the resilient reed to spring back to short-circuiting position. This return movement is greatly assisted by the action of the modifying coil 17 which, 35 as soon as energized, opposes the main coil 16 and tends to annul the effectiveness thereof. The resilient reed is thereby permitted to spring back more quickly than would otherwise be the case. Another effect of 40 the modifying coil 17 is that the reed will spring back upon a much less reduction in voltage of the main coil 16 than would otherwise be the case. As soon as the resilient reed is returned to initial position, 45 the above cycle of operation is repeated rapidly or at high frequency, the reed being kept in a state of rapid vibration. Inasmuch as the reed is attracted and released upon very slight variations in voltage, the 50 fluctuations in voltage of the translating circuit are almost imperceptible, the rise and fall in voltage being checked within very narrow limits. Due to the time lag in the operating magnet 6, said magnet cannot attain 55 its maximum strength the instant the short circuit is open nor fall to the minimum the instant the short circuit is closed. As a result, the energization of this magnet fluctuates within narrow limits, the mean 60 energization of said magnet depending on the character of said vibrations.

It is understood, of course, that the above embodiment of my invention is selected for the purpose of illustration only, as other embodiments may be devised which will fall

within the scope of the invention as expressed in the appended claims.

What I claim as new and desire to secure by Letters Patent of the United States is—

1. In an electric regulator, a main operating means, separable contacts, one of which is adapted to vibrate rapidly to open and close a shunt circuit around said operating means, and a controlling magnet for controlling said vibrations, said magnet comprising a main coil and an auxiliary coil 75 acting differentially with respect thereto.

2. In an electric regulator, a main operating winding, separable contacts, one of which is adapted to vibrate rapidly to open 80 and close a shunt circuit around said operating winding, and a controlling magnet for controlling said vibrations, said magnet comprising a main coil and an auxiliary coil, the latter being connected in series with 85 said operating winding and acting differentially with respect to said main coil.

3. In an electric regulator, a main operating means, separable contacts, one of which is adapted to vibrate rapidly to open 90 and close a shunt circuit around said operating means, and a controlling magnet for controlling said vibrations, said magnet comprising a main coil and an auxiliary coil connected in parallel with said separable 95 contacts, said two coils acting differentially.

4. In an electric regulator, a regulating medium, an operating winding for the regulating medium, separable contacts adapted to open and close a shunt circuit around said winding at a rapid rate to control the mean energization thereof, a main controlling coil for said separable contacts and a modifying controlling coil therefor, said coils acting differentially. 100

5. In an electric regulator, a regulating medium, an operating winding for the regulating medium, separable contacts adapted to open and close a shunt circuit around said winding at a rapid rate to control the mean energization thereof, a main controlling coil for said separable contacts and a modifying controlling coil therefor connected in series with said operating winding, said coils acting differentially. 110

6. In an electric regulator, a regulating medium, an operating winding for the regulating medium, separable contacts adapted to open and close a shunt circuit around said winding at a rapid rate to control the mean 120 energization thereof, a main controlling coil for said separable contacts and a modifying controlling coil therefor connected in parallel with said separable contacts, said coils acting differentially.

7. In an electric regulator, a regulating medium adapted to be connected in the circuit to be regulated, an operating winding therefor, separable electrodes adapted to rapidly open and close a shunt circuit 130

around said winding to control the energization thereof and a controlling magnet for controlling the action of said separable electrodes, said controlling magnet comprising 5 two differentially acting coils.

8. In an electric regulator, a regulating medium adapted to be connected in the circuit to be regulated, an operating winding therefor, separable electrodes adapted to 10 rapidly open and close a shunt circuit around said winding to control the energization thereof and a controlling magnet for controlling the action of said separable electrodes, said controlling magnet comprising 15 two differentially acting coils, one of which is connected in parallel with said separable contacts.

9. In an electric regulator, a regulating medium adapted to be connected in the circuit to be regulated, an operating winding therefor, separable electrodes adapted to rapidly open and close a shunt circuit around said winding to control the energization thereof and a controlling magnet for 25 controlling the action of said separable electrodes, said controlling magnet comprising two differentially acting coils, one of said coils being connected in series with said operating winding.

10. In an electric regulator, a regulating medium adapted to be connected in the circuit to be regulated, an operating winding therefor, separable electrodes adapted to rapidly open and close a shunt circuit 35 around said winding to control the energization thereof and a controlling magnet for controlling the action of said separable electrodes, said controlling magnet comprising two differentially acting coils, one of which 40 is connected across the circuit to be regulated and the other of which is connected in series with said operating winding around said separable contacts, whereby said last mentioned coil is energized when said operating 45 winding is energized and short-circuited when said operating winding is short-circuited.

11. In combination, a circuit to be regulated, a variable pressure rheostat connected 50 in series in said circuit, an operating winding for said variable pressure rheostat, a main controlling coil controlling a shunt circuit around said operating winding and a modifying coil associated with said main 55 coil and acting differentially with respect thereto.

12. In a system of electrical regulation, a variable pressure rheostat connected in the circuit to be regulated, an operating winding therefor, a shunt circuit around said operating winding, separable contacts in said shunt circuit, one of which is adapted to vibrate rapidly to open and close said shunt circuit and thereby control the energization 65 of said winding, a main controlling winding

connected across the circuit to be regulated and adapted to control said vibrations, and an auxiliary coil associated with said main coil and acting differentially to compensate for the varying reluctance of the air gap, 70 whereby said vibrations are accelerated.

13. A regulator for an electric circuit including a series of contacting carbon plates for varying the resistance of said circuit, a lever and a core for varying said resistance, a controlling winding for operating said core and lever, and a short circuit including a relay for normally short-circuiting said controlling winding, said relay being adapted to open said short circuit for successive 80 short intervals of time for regulating purposes, said relay including a contacting device, a voltage coil for operating said contacting device and a differential coil normally short-circuited by said contact device. 85

14. A regulator for a car lighting system including a circuit to be regulated, a variable resistance connected in series with said circuit and comprising contacting carbon plates, means for varying the pressure on 90 said plates, said means including a solenoid, a core controlled thereby, a bell crank lever connected with said core and a relay device for controlling the energization of said solenoid, said device comprising a spring-actuated magnetic member, a contact mounted on said member, a stationary contact co-operating with said first mentioned contact to short-circuit said solenoid, a voltage coil for moving said spring-actuated member, and a 100 differential coil normally short circuited when said solenoid is short-circuited and energized when said solenoid is energized to oppose said voltage coil and accelerate the return movement of said spring-actuated 105 member to again short-circuit said solenoid and differential coil whereby a rapid vibration of said spring actuated member is effected.

15. A regulator for a car lighting system 110 including a circuit to be regulated, a variable resistance responsive to pressure in series with said circuit, a solenoid for controlling said variable resistance, a short-circuiting device adapted to vibrate rapidly for 115 varying the energization of said solenoid, a voltage responsive coil for causing said vibrations whereby, upon increase of voltage, an increased current is permitted to energize said solenoid for successively longer intervals of time for magnifying the effect of 120 said voltage increase, and means for accelerating said vibrations, said last means including a coil connected in a circuit across the contacts of said short-circuiting device. 125

16. An automatic electric regulator having an operating winding, means arranged in a shunt circuit around said winding for varying the amount of current diverted around the same to vary the energization 130

- thereof, and auxiliary means for causing said first means to respond to very minute variations in impressed voltage to increase the sensitiveness of the regulator, said last means including a coil in a circuit in shunt to said first mentioned means.
17. A regulator including a variable pressure rheostat, a controlling solenoid for said rheostat, and a short circuit including a vibrating relay device for normally short-circuiting said solenoid, said relay being adapted to open said short circuit intermittently for regulating purposes, said relay being responsive to variations in voltage and including a contact device, a voltage coil for operating said contact device, and a differential coil connected in series with said controlling solenoid and normally short-circuited by said contact device.
18. A regulator comprising carbon plates arranged to form part of an electric circuit, a lever connected to a movable core for varying the pressure on the series of plates to vary the resistance of the circuit, a controlling winding for operating said core, and a short circuit including a relay device for normally short-circuiting said winding said relay device being adapted to open said short circuit at rapid intervals for regulating purposes, said relay being responsive to voltage rise on said circuit and including a contact device, a voltage coil for operating the contact device and a differential coil connected in series to said winding and normally short-circuited by said contact device.
19. A car lighting system including, in combination, a translation circuit, a variable pressure rheostat connected in series with said circuit, means for varying the resistance of said rheostat, said means including an electro-magnetic winding connected across said circuit and short-circuiting means for varying the strength of said winding, said means including a contact make and break device, a voltage responsive coil for rapidly vibrating said make and break device, and an auxiliary coil for opposing said voltage coil under certain conditions to accelerate the vibrations, said auxiliary coil being short-circuited when said winding is short-circuited.
20. A circuit, and means for regulating said circuit, said means including an operating coil, means for controlling the energization of said coil, said controlling means including a second coil operating responsive to varying conditions in the circuit to be regulated to increase or decrease the energization of said first coil, and means for increasing the effectiveness of said last coil
- during the time it is decreasing the energization of said first coil and for decreasing the effectiveness thereof during the time it is increasing the energization of said coil, said last means including a coil adapted to be short-circuited during the period when the effectiveness of the first coil is a minimum.
21. In combination, a translation circuit to be regulated, a compressible resistance rheostat in series in said circuit, a coil for operating said rheostat, a vibrating member including a contact for regulating the current in said coil, a coil for operating said member and contact, responsive to voltage variations of the circuit, a second contact co-operating with said vibrating contact, and a coil for decreasing the attractive force on said member when it is attracted by said attracting coil, said last mentioned coil being connected in a shunt circuit around said contacts.
22. In an electric regulator, in combination with a variable resistance adapted to be connected in the circuit to be regulated, an operating winding for controlling said resistance, a shunt circuit around said operating winding, contacts in said shunt circuit normally in contact, one of which is adapted to vibrate rapidly to open and close said shunt circuit at a rapid rate, a controlling winding for causing said vibrations, and an auxiliary coil connected in a circuit across said contacts for accelerating said vibrations.
23. An automatic electric regulator comprising a variable resistance, an electro-magnetic winding for varying said resistance, a resistance in series with said winding, a voltage responsive relay for short-circuiting said winding at a rapid rate, without short-circuiting the second mentioned resistance, and an auxiliary coil connected in a circuit across the contacts of said relay for accelerating said vibrations.
24. In combination, a translation circuit to be regulated, a compressible resistance rheostat in series in said circuit, a coil for operating said rheostat, a vibratile reed armature and co-operating contact for regulating the current in said coil, a coil for attracting said armature responsive to voltage variations of the circuit and a coil for decreasing the attractive force on said armature when it is attracted by said attracting coil.
- In witness whereof, I have hereunto subscribed my name.

JOHN W. JEPSON.
